ADJUSTABLE DOOR BRACE

Paul W. Leffland, Dallas, Tex.

Application February 3, 1933, Serial No. 655,012

15 Claims. (Cl. 20—38)

This present invention is concerned with the provision of an ornamental, protective and non-sag grille for screen doors which is designed to protect the screen cloth of the door to which the said grille is attached and further is designed to prevent the said door from sagging due to the weight and the usage of the door and due to the added weight of the said grille upon the door.

10 Previous attempts to solve the problem of door grilles by the use of grilles designed primarily for their ornamental and protective features have been unsatisfactory due to the fact that the added weight of the grille upon the door has increased the amount of sag in the said door and in numerous cases rendered the door inoperative.

In accordance with the present invention, I have designed a door grille which is an ornamental grille, a protective grille and a non-sag grille and which will overcome the above noted disadvantage and which may be conveniently and expeditiously applied to any screen door of standard type.

25 A further object of the invention is to provide the said non-sag feature in such a manner that it may be embodied into the design of the grille. It may be noted that the design of the grille is of great importance inasmuch as the main entrance doors of the home are those primarily provided with protective grilles.

30 A further object of the invention is to provide a grille which is the same upon either face in order that it may be applied and the non-sag feature used in connection with either a right hand swing door or a left hand swing door.

Other objects of the invention are to provide a grille of the character described, which will be simple, practical construction, durable and efficient in use, and well suited to the requirements of economical manufacture.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

50 Figures 1, 2, 3, 4 and 5 respectively, are views in elevation of screen doors showing some of my various designs of adjustable grilles attached which embody the feature of my new non-sag means.

55 Figure 6 is an enlarged view in elevation show-

ing my preferred construction and anchorage of my non-sag element to the door.

Figure 7 is an enlarged view of a portion of Figure 1.

Figure 8 is a section taken upon line 9—9 of Figure 7.

Figure 9 is an enlarged view of a portion of Figure 5.

Figure 10 is a section taken upon line 12—12 of Figure 9.

Referring to the drawings in detail, Figure 1 shows a detail of a simple form of my grille embodying my new invention. I have used the reference numeral 10 to indicate a screen door, and the numeral 11 to designate a grille attached thereto and serving as a protection for the screen cloth 12. I use 13 to indicate hinges upon which the said door swings, while 14 indicates my diagonal non-sag element embodied into the design of the said grille and designed to hold the said door 10 from sagging. Included in 14

15 I have placed the adjustment means 15 in order to vary the tension of 14 between the fastening points 17 when required by the condition of the said door 10, substantially as shown. The numeral 16 indicates a construction at the contact point of 14 with the door stile, shown more in detail in Figure 6. The said construction at this contact point is primarily intended to render 14

20 taut between its fastening points 17, however the loose end of the scroll as shown may be drawn in or out as required. The sharp bend 16 is of course designed to allow for this while the screw 17 directly against 16 is designed to be tightly drawn up. The adjustment means for the element 14 as indicated by 15 I show as the turn-

25 buckle type in which I employ an ornamental threaded turnbuckle with threaded rods 24 and turning slots 22. This is, of course, a simple means of adjustment however other means of adjustment may be employed of course without departing from the spirit of the invention. The numeral 20 indicates means for another adjustment between 14 and 15 which would be desirable

30 after a great amount of slack had been taken up by use of the adjustment 15 and a reset may be desired. This is of course best accomplished by blocking up a corner of the said door for the purpose. The numeral 21 indicates means for

35 tying the said 14 to the grille proper in close proximity to 15 in order to hold 14 from turning when 15 is being turned. The numeral 18 indicates pivotal adjustment points used in varying the size of the grille to fit various openings.

40 The numeral 19 shows pivotal adjustment means

45

50

55

at the center of the grille. This is illustrated in detail in Figures 7 and 8.

While the description above is given for Figure 1 it likewise applies to Figures 2, 3, 4 and 5 wherein like numerals of reference such as 11a, 11b, 11c and 11d indicate a grille in the same manner that 11 indicates a grille in Figure 1.

The five designs of grilles as shown in the drawings are taken as modifications of designs 10 which may be applied in my invention, however in Figure 4 I show modifications of grilles in other forms than in design only. For instance the Figures 1, 2, 3 and 5 respectively show various 15 types of scroll constructed grilles while Figure 4 shows a modification in which the grille proper is of woven mesh construction.

Referring to Figures 2 and 3 of the scroll constructed grille the numeral of reference 23 (not applying to Figure 1) indicates a slip collar for 20 the slip movement of the member within the said collar as shown.

Referring to Figures 3, 4 and 5 the numeral 18 indicates another type of grille size adjustment means than that indicated for Figures 1 and 2 25 and described as pivotal. In this modified grille size adjustment the scroll member 18b, 18c and 18d is designed to be manually sprung to fit various sizes of doors.

Referring to Figures 9 and 10 I have shown a 30 modified adjustment means 15d for the adjustment of said elements 14d. In this modification it is of course the intention to make the adjustment means symmetrical. Consequently, I employ the crossing members 25 fastened together by 35 the means 26 and designed to allow for the pivotal and other operation of 15d thru said 25 as at 27.

In Figure 9 I show 14d as a modification of 14 in that I employ a plurality of members combined 40 to form said 14d.

Referring to the resetting means 20 indicated in Figure 1 and shown in detail in Figure 7 the threaded rod 24 is shown beveled at 20 and is preferably squared at this end while the element 45 14 is of course punched at 20 to receive said beveled and squared end. Figure 1 and the other designs shown may apply.

When the grille has been applied to a door having an exceptional amount of sag the adjustment means 15 is of course employed to square 50 up the door after which the door may be blocked up and 15 loosened and a reset made at 20 as desired. The slack may then be taken up by means of 15 as required to leave the 55 grille design in proper form or configuration. In Figure 9 however I have shown 20d modified in which a removable pin may be inserted at 30 to hold 24d from turning substantially as does the squared end method employed and shown.

60 The resetting means however may be omitted if desired for economic reasons.

My new grille will be of course preferably 65 constructed alike on either side and also have the holes for fastening as 16 in the center of the several grille members in order that the grille may be applied in either right hand or left hand swing doors.

It may be noted that the adjustment furnished 70 by the means 15 will be required from time to time inasmuch as the entrance screen door is usually exposed to the action of various weather conditions and this in conjunction with the great amount of usage to which the average entrance screen door is subjected naturally will require 75 adjustments against sagging.

It may be noted that the structure has broader uses than the specific embodiment of a grille in a screen door. For instance it may be used in other types of doors.

Obviously, various changes and alterations 5 might be made in the general form and arrangement of the parts described without departing from the invention. Hence I do not wish to limit myself to the details set forth, but shall consider myself at liberty to make such changes 10 and alterations as fairly fall within the spirit and scope of the appended claims.

I claim:

1. A door brace comprising a plurality of spaced metallic bands, crossed at substantially 15 right angles by a plurality of like bands; pivotal engagements between the said bands at the points where they cross, to form an expandible grille; one transverse band to have means near its ends for firmly attaching it to the door, said band to be bent in a sharp angle at each point of attachment to the door; and the free ends of said band, beyond its point of attachment to the door, returned in loose scrolls to form ornamental protection to the door. 20

2. A door brace comprising a plurality of spaced metallic bands, crossed at substantially 25 right angles by a plurality of like bands; pivotal engagements between the said bands at the points where they cross, to form an expandible grille; one transverse band to have means near its ends for firmly attaching it to the door, said band to be bent in a sharp angle at each point of attachment to the door; the free ends of said band, beyond its point of attachment to the door, returned in loose scrolls to form ornamental protection to the door; and means within said band for contracting and shortening the same so that the door may be supported and braced. 30

3. A door brace comprising a plurality of spaced 35 metallic bands, crossed at substantially right angles by a plurality of like bands, pivotal engagements between the said bands at the points where they cross, to form an expandible grille; means near the ends of said bands for firmly attaching 40 them to the stiles and cross rails of a door; and free ends of said bands, beyond the points of attachment to the door, returned in loose scrolls to ornament and protect the door. 45

4. A door brace comprising a plurality of spaced 50 metallic bands, crossed at substantially right angles by a plurality of like bands; pivotal engagements between the said bands at the points where they cross, to form an expandible grille; means near the ends of said bands for firmly attaching 55 them to the stiles and cross rails of a door; and a turn-buckle within one band, replacing a segment removed therefrom, so that by operating the turn-buckle the said band may be shortened 60 to brace the door; and the free ends of said bands, beyond their points of attachment to the door, returned in loose scrolls to form ornamental protection to the door. 65

5. A door brace comprising a plurality of spaced 70 metallic bands, crossed at substantially right angles by a plurality of like bands; pivotal engagements between the said bands at the points where they cross, to form an expandible grille; means near the ends of said bands for firmly attaching 75 them to the stiles and cross rails of a door; a turn-buckle within one band, replacing a segment removed therefrom, so that by operating the turn-buckle the said band may be shortened 80 to brace the door; slots within the band to which the turn-buckle is attached, said slots being so 85

disposed that one slot is on one side the turn-buckle and another slot on the other side the turn-buckle; and a substantially circular band, passing through said slots, being firmly affixed 5 to a band disposed at substantially right angles to the turn-buckle band, whereby the turn-buckle band may be guided and kept in place.

6. In a screen door brace, a plurality of diagonally disposed straps, spaced in substantially 10 parallel relation, a plurality of like straps, crossing the first named straps at substantially right angles; means for effecting pivotal engagements between the straps at the points where they cross one another; one of said first named plurality of 15 straps having a plurality of slots within its body, and having a turn-buckle within its body, so that the said strap may be shortened or lengthened; one of the second named plurality of straps having within its body a substantially circular section, said circular section made to pass freely 20 through the said slots; means for attaching all of the aforesaid straps, near their ends, with the side and cross members of a screen door, whereby, upon operation of the turn-buckle, the unhinged 25 side of the door may be supported, and the screen wire protected.

7. In a screen door brace, a plurality of metallic rods spaced in substantially parallel relation, a plurality of like rods crossing the first named 30 rods, and means for effecting pivotal engagements between the rods at their crossing points; contracting means within one rod so that its length may be decreased; and guiding means within a rod crossing the contracting rod, so that 35 said guiding means will prevent any substantial deflection of the contracting rod from the general vertical plane of the brace.

8. In a door brace, a plurality of spaced metallic bands, crossed at substantially right angles 40 by a plurality of like bands; pivotal engagements between the said bands at the points where they cross, to form an expansible grille; means near the ends of said bands for firmly attaching them to the stiles and cross rails of a door; and contracting means within one band, whereby the 45 said band may be shortened to brace the door.

9. In a door brace, a plurality of spaced metallic bands, crossed at substantially right angles by a plurality of like bands, pivotal engagements 50 between the said bands at the points where they cross, to form an expansible grille; means near the ends of said bands for firmly attaching them to the stiles and cross rails of a door; contracting means within one band, whereby the said 55 band may be shortened to brace the door; and guiding means within one band which crosses the contracting band, whereby the latter may be guided and held in place.

10. In a door brace, a plurality of spaced metallic bands, crossed at substantially right angles 60 by a plurality of like bands; pivotal engagements between the said bands at the points where they cross, to form an expansible grille; means near the ends of said bands for firmly attaching them 65 to the stiles and cross rails of a door; free ends

of said bands, beyond their points of attachment to the door, returned in loose scrolls to ornament and protect the door; and means within one band whereby the said band may be shortened to brace the door.

11. In a door brace, a plurality of spaced, flexible metallic bands disposed substantially within a single plane; means near the ends of said bands for connecting the bands with one another to form an expansible grille; means near the ends 10 of one of said bands for firmly attaching it to a door; and contracting means within said last named band whereby it may be shortened to support and brace the door.

12. In a door brace, a plurality of spaced, flexible metallic bands disposed within a single plane; means near the ends of said bands for connecting the bands with one another to form an expansible grille; means near the ends of one of said bands for firmly attaching it to a door; contracting means within said last named band whereby it may be shortened to support and brace the door; flexible metallic scrolls disposed within the plane of said grille and on alternate sides thereof; means whereby said scrolls may be connected 20 to the door and to the grille to support the latter.

13. In a door brace, two diagonally disposed metallic rods crossing one another at substantially right angles; means near the ends of each of said rods for firmly affixing them to a door; 30 contracting means within one of said rods whereby it may be shortened to support and brace the door; a rectangular metallic frame disposed substantially within the plane of said crossed rods; means near each of the corners of said frame 35 for attachment to the said rods, whereby the frame may be supported on the rods; and protective wire netting covering said metallic frame.

14. In a door brace, two diagonally disposed metallic rods crossing one another at substantially right angles; means near the ends of each of said rods for firmly affixing them to a door; contracting means within one of said rods whereby it may be shortened to support and brace the door; a rectangular metallic frame disposed substantially 40 within the plane of said crossed rods; means near each of the corners of said frame for attachment to the said rods, whereby the frame may be supported on the rods; protective wire netting covering said metallic frame; and 45 ornamental wire scrolls disposed about and attached to the periphery of said frame to ornament and protect the door.

15. In a door brace, a plurality of flexible, ornamental, metallic scrolls disposed within a single 50 plane of substantially rectangular design to form a grille; means for firmly attaching said scrolls at points near their outer extremities to the door; a plurality of metallic rods, each connecting to two of said scrolls oppositely disposed to one 55 another; contracting means within one of said rods whereby the distance between the scrolls connected by said rods may be shortened to support and brace the door.
